C. W. HADLEY.
ELEVATING MACHINE.
APPLICATION FILED DEC. 26, 1912,

Patented May 15, 1917.

UNITED STATES PATENT OFFICE.

CHARLES W. HADLEY, OF OGDEN, UTAH.

ELEVATING-MACHINE.

1,225,809.

Specification of Letters Patent. Patented May 15, 1917.

Application filed December 26, 1912. Serial No. 738,679.

To all whom it may concern:

Be it known that I, CHARLES W. HADLEY, a citizen of the United States, residing at Ogden, in the county of Weber and State of Utah, have invented a new and useful Elevating-Machine, of which the following is a specification.

My invention is an improvement in elevators for grain and other commodities, where-
10 by the contents of the buckets are forcibly ejected, and admits of running of the machine at any speed, without danger of cupping the contents down.

While the above is the principal object of
15 my invention, I have also provided means whereby the device can be quickly transformed into an elevator of the ordinary type.

The principle and operation of my machine is plainly illustrated by the accom-
20 panying drawings, in which—

Figure 1 is a vertical section of the entire machine; Fig. 2, is a vertical section of the same, showing the transformation into the ordinary elevator. While pulleys and belts
25 and sprocket wheels and chains can either be used with my machine and any commodity be elevated, for my illustration, I have used pulleys, and grain to elevate.

In Fig. 1, A is the main pulley and B is
30 an idler pulley, preferably smaller, in front of and near to pulley A. D designates the belt having a plurality of buckets thereon and for the purpose of further description certain of the same are designated by the let-
ters E, E' and E''. G is a tilting bracket, carried by the shaft F and holding the bearings G and G' for the pulleys A and B. H is the lower pulley of the elevator and I is a hopper. Suitable supporting means is

35 provided for this device and is designated by the numeral 10, the same having means whereby the pulley H is journaled thereto and also for the journaling of the shaft F that carries the bracket C. As is shown in
40 Fig. 2, the bracket C is tilted forward to change the machine to a single pulley elevator, and for accomplishing this purpose I have provided on the shaft F fast thereto, a sprocket wheel J and journaled in the sup-

45 port 10 a sprocket wheel L having a lever or operating handle K thereon. A chain M is trained over these sprocket wheels J and L and movement of one will necessarily impart motion to the other. It is of course obvious
50 that this handle or lever K is within access of the operator so that the machine can be

changed to assume the position shown in Figs. 1 or 2 at will.

The pulleys A and B are so proportioned in size and the bracket C so centered on
60 shaft F that the tension of belt D is not altered during the change, which can be made while the machine is in motion.

The operation of the machine is as follows, reference being had to Fig. 1. The buckets 65 E in passing around pulley H are filled with grain and carried over pulleys A and B and the contents deposited as desired. Up to the time at which the bucket E reaches such a position that its center is in the same horizontal plane as the axis of shaft g' of pulley A, the bucket and belt have moved at the same speed. In passing around pulley A to position of bucket E', the bucket and contents has moved faster than the belt in pro-
70 portion as it is more distant from the center of motion. From position of E' toward pulley B, the bucket again moves at the same speed as the belt, but the grain continues at the greater speed and is beyond the reach of 75 80 the bucket as it passes around pulley B. This is true without regard to the speed of the machine.

Referring to Fig. 2. In case it is desired to use the machine as the ordinary one pulley 85 elevator, all that is necessary, is to tilt, by lever or otherwise, the bracket C forward, bringing pulley A to the front and dropping pulley B from connection. This can be done
90 while the machine is in motion.

The advantages claimed for my machine over the old style are—In the machines now in use, the contents must be flinted from the buckets, in case of a perpendicular machine. In case of an inclined machine, gravitation 95 added to the speed of the bucket clears the grain from cupping, and in either case the speed must be carefully regulated. In my improved elevator, whether it be perpendicular or inclined, the grain is forcibly ejected 100 from the bucket without regard to speed. The change to the ordinary machine can be made by a lever.

I am aware that there are elevators which have pulleys in advance of the main pulley 105 which carry the chain and buckets to varying distances but in all such cases, the contents of the buckets are either dropped between the pulleys or are carried in the buckets over the second pulley, while in my machine, the pulleys are nearly in contact and the buckets have no connection with, nor con-

trol over the contents after leaving the main pulley.

I claim:

1. In elevating machines, the combination 5 of a multiple-run conveyer; and means for increasing or diminishing the number of runs of the conveyer, optionally.

2. In elevating machines, the combination 10 of a multiple-run conveyer, and means for increasing or diminishing the number of runs of the conveyer, optionally, during the operation of the conveyer.

3. In elevating machines, the combination 15 of a lower pulley, two upper pulleys mounted in spaced relation, a belt passed about all of said pulleys, and means for moving one of said upper pulleys out of engagement with said belt and for simultaneously raising the other said pulley, whereby the conveyer can be converted from a three-run into a two-run conveyer, optionally, and said belt maintained under constant tension.

4. In elevating machines, the combination 25 of a pulley, a tiltably journaled bracket, two pulleys carried by said bracket and mounted in spaced relation, a belt passed about all of said pulleys, the pulleys carried by said bracket being inside of the runs of the belt, and means for tilting said bracket.

5. In elevating machines, the combination 30 of a pulley, a tiltably journaled bracket, two pulleys carried by said bracket and mounted in spaced relation and closely adjacent each other, a belt passed about all of said pulleys, the pulleys carried by said bracket 35 being inside of the runs of said belt, and means for tilting the bracket.

6. In elevating machines, a conveyer, and means for converting said conveyer into a two-run gravity-discharge conveyer, or a 40 three-run centrifugal-discharge conveyer, optionally.

7. An elevating machine including supporting means carrying an axle provided with a driven pulley, an axle at the other 45 end of said supporting means and parallel with said first named axle, a bracket journaled on said last mentioned axle and carrying idler pulleys, a belt running over all of said pulleys and provided with conveyer buckets, and means for shifting said bracket to throw one of said idler pulleys out of engagement with said belt. 50

CHARLES W. HADLEY.
